UNITED STATES PATENT OFFICE.

JOHN V. PALMER, OF PITTSBURGH, PENNSYLVANIA.

CHAIR.

1,357,469.

Specification of Letters Patent. Patented Nov. 2, 1920.

Application filed June 26, 1920. Serial No. 391,883.

To all whom it may concern:

Be it known that I, JOHN V. PALMER, a citizen of the United States, residing at Pittsburgh, in the county of Allegheny and State of Pennsylvania, have invented certain new and useful Improvements in Chairs, of which the following is a specification.

This invention relates to chairs of the type disclosed in Letters Patent, No. 1,301,001, granted to me April 15, 1919, the object of the present improvements being to simplify the construction and reduce the cost of manufacture without any loss of efficiency.

5 In the drawings:

Figure 1 is a perspective view of a dining room chair having my invention applied thereto and showing it as it appears for use in the usual manner;

0 Fig. 2 is a similar view showing the highchair arranged for use;

Fig. 3 is a similar view, showing the highchair folded;

Fig. 4 is a longitudinal section through the seat and seat frame of the dining chair and showing the highchair housed therein;

Fig. 5 is a view, partly in section and partly in elevation, showing the assemblage of the parts prior to the lowering of the 0 chair seat;

Fig. 6 is a detail section showing means for retaining the side members of the highchair in closed position.

The dining chair may be of any approved design embodying a back 1, legs 2 and a seat frame 3. The seat 4 of the dining chair may be provided with a cushion 5 and is utilized as the back of the highchair when the latter is in use. The seat is provided at its rear edge with a bar or cleat 6 which is secured rigidly to the seat proper at a right angle thereto and is intended to fit within the seat frame in normal position, as shown in Fig. 4. To the free edge of this bar, cleat or rail 6 I secure, by hinges 7, a foot plate 8 which is adapted to provide a rest for the feet of the child when the highchair is in use and when in use fit within a notch or recess 9 provided in the front rail of the seat frame 3. When the highchair is not in use the plate 8 is supported by a rest 10 secured to the front rail of the seat frame 3 and projecting rearwardly therefrom, as clearly shown in Fig. 4, it being noted that the upper surface of this support is inclined downwardly from the base

of the recess to the bottom of the seat frame so that as the seat is raised the front edge of the foot rest will be guided into the recess and will be supported at all times. 60 Upon the under side of the seat 4 parallel with the side edges of the same and near the side edges, I secure cleats or strips 11 to which are secured, by hinges 12, the side members 13 of the highchair. These side members 13 may be solid, as illustrated in the drawings, or may be of any other preferred design and they are extended, at their free edges, to provide feet 14 which are adapted to rest upon the side bars of the 65 seat frame when the highchair is in use, as shown in Fig. 4. On their inner faces, the side members are provided with ribs or flanges 15 to support the seat member 16 hinged at its rear edge to the under side 70 of the seat 4 and adapted to fit between the side members and rest on the said flanges, as clearly shown in Fig. 2.

The side members 13 are equipped along their upper edges with longitudinally curved 80 cleats 19 whereby sockets or chambers are provided to receive the side extensions or arms 20 of the tray 21, and spring latches 22 may be provided upon the side members at the front edges thereof to engage the said side arms or extensions and thereby hold the tray in its proper operative position when the highchair is in use. When the highchair is to be folded the tray is withdrawn from its engagement with the side members and is 85 placed flat upon the foot rest 8.

When the device is arranged for use as a highchair the chair seat 4 is swung upwardly about its hinged connection 25 with the chair frame so as to rest against the back 1 of the 95 chair. The side members are then swung out to stand at right angles to the chair seat 4 and the highchair seat 16 is swung downwardly to the position shown in Fig. 2. When the chair seat 4 is swung upwardly to 100 the position shown in Fig. 3, the plate or foot rest 8 will be lifted at its rear end through its hinged connection with the rail 6, and will slide into engagement with the recess or notch 9 so that it will be firmly supported and furnish a firm rest for the child's feet. After the child is seated the tray 21 is brought into position by engaging its side arms or extensions 20 in the cleats 19 and permitting the latch 22 to operate, as will be 105 readily understood. When the highchair is no longer to be used the tray is removed, the

seat 16 folded against the combined back and seat 4, after which the side members 13 are folded over across the seat. The tray is placed upon the foot rest 8 and the folded device swung forwardly and downwardly to be supported by the rest 10 and housed within the seat frame. The dining chair may then be used in the usual manner.

When the side members 13 are folded, as shown in Fig. 3, their lower extensions 14 will ride over spring-pressed buttons 17 carried by the rail 6 at the center thereof, said buttons engaging sockets 18 in the extensions 14, as shown in Fig. 6, and retaining the side members in the folded position.

The side plates are provided with latches 26 which are adapted to engage keeper lugs 27 on the seat frame 3 when the highchair is not in use so as to prevent lifting of the seat 4 when the chair is being moved.

My device is exceedingly simple in the construction and arrangement of its parts and may be very easily adjusted. When adjusted for use as a highchair it will be firmly supported and cannot collapse while a child is seated therein. Obviously, the foldable highchair may be applied to dining chairs now in use as well as chairs which may be hereafter made and it does not constitute an odd piece of furniture or interfere with the ordinary use of the chair in any way.

Having thus described the invention, what is claimed as new is:

1. In a chair, the combination of a seat frame, a chair seat hinged at the rear of the said seat frame, the front portion of the seat frame being provided with a recess in its upper edge, a guiding support leading up to said recess, a plate hingedly connected with the chair seat and having its free end adapted to engage said recess and bear upon said support, and a collapsible seat mounted upon the under side of said chair seat.

2. In a chair, the combination of a seat frame, a chair seat hingedly secured upon said seat frame, rails secured to the under side of said chair seat near the side edges thereof, a supplemental seat hinged to the under side of the chair seat between said rails to fold against the chair seat, side members hinged to said rails to swing across the supplemental seat and provided with supports for said supplemental seat, said side members being provided with extensions to rest upon the sides of the seat frame when extended, and means on the rear of the chair seat to engage said extensions and retain the side members in folded position, said means when active being housed by the extensions and the chair seat.

In testimony whereof I affix my signature.

JOHN V. PALMER. [L. s.]
